United States Patent Office

Des. 203,874

Patented Feb. 22, 1966

203,874

FACE PANEL FOR A CONTROL INSTRUMENT

Ronald C. Miller, Norristown, Pa., assignor to Honeywell
Inc., a corporation of Delaware

Filed Jan. 15, 1965, Ser. No. 83,462

Term of patent 14 years

(Cl. D52—6)

FIG. 1

FIG. 2

FIG. 1 is a front elevational view of the face panel for a control instrument, showing my new design;
FIG. 2 is a front perspective view thereof.

The undisclosed side of the control instrument face is substantially the same in appearance as the side shown.

I claim:

The ornamental design for a face panel for a control instrument, substantially as shown and described.
